UNITED STATES PATENT OFFICE.

WILLIS BENNER, OF ST. PAUL, MINNESOTA.

DARK-LANTERN.

SPECIFICATION forming part of Letters Patent No. 339,846, dated April 13, 1886

Application filed November 17, 1885. Serial No. 183,078. (No model.)

To all whom it may concern:

Be it known that I, WILLIS BENNER, a citizen of the United States, residing at St. Paul, in the county of Ramsey and State of Minnesota, have invented certain new and useful Improvements in Dark-Lanterns; and I do hereby declare that the following is a full, clear, and exact description thereof, reference being had to the accompanying drawings, in which—
10 Figure 1 shows a vertical sectional view of an ordinary bull's-eye or dark-lantern with my improved means and devices for shutting off and turning on the light applied thereto; Fig. 2, a sectional view of the same on line α α of Fig. 1, looking from below, and Fig. 3 a detail perspective view of the screen-cylinder and the means for turning the same.

Letters of like name and kind refer to like parts in each of the figures.
20 The object of my invention is to provide an improved bull's-eye or dark-lantern in which the means for turning on and shutting off the light can be operated at will by the hand which carries the lantern without necessitating the use 25 of the other hand; and to this end my invention consists in the construction, arrangement, and combination of parts, as hereinafter specified.

In the drawings, A designates a bull's-eye or dark-lantern having the usual lamp, lens, 30 and holding devices or handles.

On top of the lantern-casing is the ordinary fluted cap, B, for permitting the passage of hot air or smoke from within while preventing the egress of light. Such form of cap is, however, 35 not at all essential to my invention. Both it, the casing, the lens, and the fastening device and handles can be varied in construction, as desired, without departure from or affecting my invention.

40 Within the lantern-casing and surrounding the lamp I place the cylinder C, corresponding nearly in size with the interior of the casing, so as to be steadied thereby as it is rotated, as hereinafter described. Such cylinder 45 extends well below and above the light-opening D in the casing, and is provided in one side with the opening E, preferably corresponding in size and shape with such light-opening. At 50 its upper end the cylinder is provided with the cross-bar F, to the middle of which is fast-

ened the lower end of the spiral G. From the upper end of such spiral, which is preferably formed of a flat plate or thin bar of metal twisted, as shown best in Fig. 3, the vertical supporting shaft H extends up through the 55 lantern-cap B, and is supported from the apex thereof by means of a nut, h, screwed on the shaft above the cap. I prefer to place a washer, h', on the shaft below the nut to rest on the cap-top and form a good supporting bearing for 60 the nut. With this construction the screen-cylinder C is supported simply from the lantern-cap in such a way as to be free to rotate in either direction, and, as indicated hereinbefore, is steadied in such rotation by the sides of 65 the casing. As there is usually no tendency, or scarcely any, in the cylinder to swing or vibrate, its bearing against the casing will be very slight.

Pivoted to the casing or to a lug thereon at 70 I, is the lever K, whose outer end is in position to be operated by the thumb of the hand grasping the handles to carry the lantern. The other end of the lever extends in through the casing, and is provided with the slot I, engaging the spiral G, as shown best in Fig. 3. 75 As such spiral is formed, as described, of a plate twisted, the slot need not be more than a narrow straight one to properly embrace and engage it. Instead of being slotted, as shown, 80 the lever can obviously be simply forked so that the fork will embrace the spiral. A spring, L, engaging the outer or handle end of the lever, keeps it normally elevated, and throws it up again when it has been depressed and released. 85 The normal position, then, of the inner slotted end of the lever is down, as shown in Fig. 3. The spiral G is so constructed with reference to the cylinder that when the engaging end of the lever is down the cylinder is 90 turned to bring its light-openings E away from the light-opening D to the lens. The light from the lamp within is then normally screened or shut off from the opening D. If, now, the outer end of the lever I be depressed so as to 95 raise the inner end thereof, the sides of the slot I, engaging and traveling up the spiral, will cause it and the screen-cylinder to rotate quickly to bring opening E into coincidence with light-opening D to let the whole light flash 100

out unobstructed through the lens. Upon releasing the outer end of the lever the spring throws it quickly upward again, thus causing the screen-cylinder to turn back again with its opening away from the light-opening D, as before. With this construction the turning on and cutting off the light can be done and controlled by the thumb of the hand carrying the lantern. There is then no necessity of using the other hand to turn on or shut off the light, as in the case of the dark-lanterns as heretofore made. But one hand being necessary to carry and properly operate my lantern, the other hand is free to be used as necessity requires.

15 The advantages of my lantern, where a weapon of defense has to be carried in one hand, are too obvious to need setting forth.

Instead of making the rotary screen in the form of a cylinder with a hole for the light-opening cut therein, of course only a portion of the cylinder sufficient in extent to extend across the light-opening D in the lantern-casing can be used without departure from my invention. In such case the upper rim of the cylinder to which the supporting cross-bar is attached would of course be retained, the screen portion depending from and being carried by such rim.

My lantern can obviously be used to great advantage not only for an ordinary bull's-eye or dark-lantern, but where any flashing light to be controlled by the lantern-carrier is desired, as the length or duration of the flashes of light are under perfect control.

35 Having thus described my invention, what I claim is—

1. The combination, with the lantern casing,

of a screen pivoted therein provided with an inclined cam having its opposite sides substantially parallel, and a lever engaging the cam on such opposite sides, substantially as and for the purpose described.

2. In combination with the lantern-casing, the rotary screen therein, the spiral rigidly connected with the screen, and the lever engaging such spiral, substantially as and for the purpose described.

3. In combination with the lantern, the rotary screen, the spiral rigidly connected therewith, and the lever provided with the slot through which the spiral passes, substantially as and for the purpose specified.

4. In combination with the lantern-casing, the shaft supported from the top of the lantern, the spiral, the rotary screen connected rigidly therewith, the lever slotted to engage the spiral projecting out through the casing in proximity to the handles of the lantern, and the spring engaging the lever, substantially as and for the purpose shown.

5. In a dark-lantern, in combination with the casing, the lever pivoted thereon above the handles, extending within the casing, and slotted at its inner end, the spring engaging the lever, the rotary screen within the casing, and the twisted bar or spiral rigidly connected with the screen and passing through the slot in the lever, substantially as and for the purposes set forth.

WILLIS BENNEP
